(57) **CLAIM**

The ornamental design for a belt accessory system, as shown and described.

DESCRIPTION

FIG. 1 is a front perspective view showing a belt accessory system of the new design in a position of use proximate to a belt;

FIG. 2 is a front perspective view showing an outer sleeve of the belt accessory system;

FIG. 3 is a top plan view of the outer sleeve of FIG. 2;

FIG. 4 is a front elevation view of the outer sleeve of FIG. 2;

FIG. 5 is a bottom plan view of the outer sleeve of FIG. 2;

FIG. 6 is a right elevation view of the outer sleeve of FIG. 2;

FIG. 7 is a left elevation view of the outer sleeve of FIG. 2;

FIG. 8 is a rear elevation view of the outer sleeve of FIG. 2;

FIG. 9 is a front perspective view showing another embodiment of a belt accessory system of the new design in a position of use proximate to a belt;

FIG. 10 is a front perspective view showing an outer sleeve of the belt accessory system of FIG. 9;

FIG. 11 is a top plan view of the outer sleeve of FIG. 10;

FIG. 12 is a front elevation view of the outer sleeve of FIG. 10;

FIG. 13 is a bottom plan view of the outer sleeve of FIG. 10;

FIG. 14 is a right cross-sectional elevation view of the outer sleeve taken along line 14-14 of FIG. 12;

FIG. 15 is a left cross-sectional elevation view of the outer sleeve taken along line 15-15 of FIG. 12; and,

FIG. 16 is a rear elevation view of the outer sleeve of FIG. 10.

The broken lines in the drawings illustrate the portions of the belt accessory system or environmental structure that form no part of the claimed design.
